SEMAPHORE-SIGNAL BLADE.

1,242,899.

Specification of Letters Patent.

Patented Oct. 9, 1917.

Application filed November 19, 1915. Serial No. 62,421.

To all whom it may concern:

Be it known that we, MATTHEW H. LOUGHRISE, a resident of Teaneck, county of Bergen, State of New Jersey, and RALPH P. TUTTLE, a resident of Mountainview, county of Passaic, State of New Jersey, have invented a new and useful Improvement in Semaphore-Signal Blades, of which the following is a specification.

10 This invention relates to semaphore signal blades made from sheet steel and is a continuation in part of our co-pending application, Serial No. 792,624, filed September 30, 1913.

15 The shape of signal blades of the character described in this invention has been established in the art with the use of wooden blades. These consist of a tapering member secured at the narrow end to the blade grip or spectacle casting which moves on a spindle in the arc of a circle to give different indications by the position of the blade. Wooden blades are also tapered edgewise in the opposite direction so that the broad 20 outer end is the thinner. In this way a rigid and comparatively light blade is obtained with the center of gravity concentrated nearer the blade grip than the outer end.

25 With sheet metal it is impossible to obtain an edgewise taper corresponding to the wooden blade and in order to obtain a sheet steel blade with characteristics approaching those of wooden blades certain elements enter into its construction with relation to weight and operating torque which it is the purpose of the present invention to provide. This invention also has for its objects methods of reinforcement against wind 30 pressure and for resisting the effects of jar due to the sudden stopping of the blade in its vertical movement, and to the method of attaching the blade to the blade grip. Sheet metal blades are usually enameled with a porcelain enamel and certain novel features are introduced in the present invention to facilitate this process.

Our invention is disclosed in the accompanying drawings in which, Figure 1 is a back view of the semaphore blade, Fig. 2 is a cross section on the longitudinal axis of Fig. 1. Fig. 3 is an enlarged cross section on line A—A of Fig. 1 showing method of attachment to the spectacle casting (the latter being omitted in Fig. 1 for the sake of clear-

ness), Fig. 4, is a cross section on line B—B of Fig. 1, and Fig. 5 is a front view of the spectacle casting showing spindle 36.

The blade proper consists of a light piece of sheet metal 11, the front of which is 60 coated with a porcelain enamel of any desired color. In order to give this piece sufficient rigidity to resist lateral wind pressure another sheet metal piece 12 is provided on the back. These two pieces are so 65 formed as to produce the elongated tubular cross section shown in Figs. 3 and 4.

The blade is supported at the narrow end by the blade grip or spectacle casting 18, Figs. 3 and 5. It will be observed that the 70 reinforcing piece 12 does not extend more than half way on the blade so that it is possible by this construction to obtain a comparatively light and laterally rigid blade and, at the same time, bring the center of 75 gravity closer to the point of support than is possible with a blade made entirely from one piece.

It will be noted that the edges 22 of the blade are formed into a tubular section 80 which constitutes stiffening ribs and also forms a means of attachment between 11 and 12.

The outer end of the blade is reinforced by diagonal cross braces 13—14, shown in 85 cross section at 13, Fig. 2. These are riveted to the blade and arranged to overlap the reinforcing piece 12, the point 29 of the latter falling within the vertical plane of the ends 30 of the cross braces. This prevents 90 the blade from buckling at this point and the cross braces form light reinforcing members for the broad outer end of the blade.

The reinforcing piece 12 is secured to the blade by the rivets 23 and 24. This may be 95 further secured by the rivets 25 and 27, which, with the spacers 28, forms this portion of the blade into a diagonal truss thus increasing its rigidity to resist wind pressure.

A semaphore blade of the kind described made from a single sheet of metal has a tendency to gyrate about the point of attachment to the spectacle casting, when suddenly brought to a stop in its vertical movement. This tendency is considerably aggravated by the fact that the blade is supported from its narrow end. This condition tends to weaken the blade, making it liable to fracture and, in the case of enameled blades, 105 110

cracks the enamel which scales off and allows the sheet steel to rust. The tubular construction in this invention eliminates this gyrating effect, since the blade is supported by the reinforcing member 12 on both edges. This member also forms a continuous transverse brace, the thrust from which is taken up by the rivets 24, 25 and 27. The diagonal cross braces in addition to stiffening the outer end of the blade also support the edges at points sufficiently close to prevent gyration to any appreciable extent.

The blade is secured to the blade grip 18 by the bolts 19-20, as shown in Fig. 3. For this purpose a comparatively heavy pointed plate 15 is inserted in the elongated tube and by means of the bolts firmly clamps the reinforcing plate 12 against the blade grip, thus distributing the strain of the load or weight of the blade over a large area of the light metal. To still further increase the depth of the bolt holes or slots in the blade and the bearing area of the bolts, the outer cleats 16-17 are provided. These, with plate 15, are held in place by rivets 21, countersunk as shown, on the side toward the blade grip to present a smooth surface.

The inner end of plate 15 is tapered to a point where, by rivet 26, it carries part of the weight of the blade close to its center of gravity; thus relieving the strain on the light reinforcing member 12.

The end of plate 15 is turned over at 33 to form a closure for the end of the blade; the bolt heads therefore, fall within an enclosed space and in order that they may be inserted in the slots 32 in plate 15 and cleats 16-17, gaps 31, opposite these slots, are provided in the reinforcing piece 12. The slotted holes also facilitate attaching and detaching the blade and by this construction the method of attachment is entirely concealed so that the front of the blade presents a uniform unbroken aspect to view.

In the process of manufacture it is necessary to raise the blade to a high degree of heat when applying the enamel and the effects of shrinkage when so heated and cooled must be provided for in the construction.

The cross braces 13-14 and the reinforcing piece 12 are made from the same gage metal as the blade 11 so that they will absorb and dissipate heat at the same rate and therefore will not cause warping of the blade in the enameling process. With this end in view the piece 12, although firmly, is not rigidly secured to the blade on the edges, but has, when heated, a free limited movement in the tubular edges 22.

The clamping piece 15, is of heavier gage than the blade but the rivet hole 26 is slotted

to provide for unequal expansion and the holes for rivets 21 may be similarly slotted in piece 12.

By this construction it will be seen that a superior enameled blade is obtained which has characteristics approaching a wooden blade.

Having thus described our invention we claim:

1. A tapering enameled semaphore signal blade supported at its narrow end, made from two sheets substantially of uniform gage metal with their edges joined, the supported end of said blade being of elongated tubular cross-section whereby the one sheet reinforces the other. 75

2. A tapering sheet metal semaphore blade supported at its narrow end, said blade being of elongated tubular cross section for approximately half its length and having diagonal cross braces for the remainder of its length. 80

3. The combination of a sheet metal blade, one portion of which has an elongated tubular cross section and another portion has diagonal cross braces, the ends of said cross braces extending over the same transverse section of said blade with a portion of said tubular section. 85

4. The combination of an enameled sheet metal blade of elongated tubular cross section at one end, a semaphore casting, means for attaching said blade to said semaphore casting through the back side of said elongated construction only. 90

5. The combination of an enameled semaphore blade, a reinforcing member, said member secured to the longitudinal axis of said blade and supporting its edges. 100

6. The combination of an enameled semaphore blade, a reinforcing member, said member secured to the longitudinal axis of said blade and supporting its edges but not rigidly connected thereto. 105

7. The combination of a sheet metal semaphore blade of elongated tubular cross section, a semaphore casting, a clamping plate inserted in said tubular section, said plate clamping one side of said tubular blade to said semaphore casting. 110

In witness whereof, we have hereunto subscribed our signatures in the presence of witnesses.
